SPRAY VALVE

Thomas W. Kellogg, Duarte, Calif., assignor of small percentages to various assignees

Application January 12, 1959, Serial No. 54,150

Term of patent 14 years

(Cl. D91—3)

Figure 1 is a perspective view of the spray valve showing my new design;

Figure 2 is a side elevation of the spray valve;

Figure 3 is a front end view of the spray valve;

Figure 4 is a top plan view of the same;

Figure 5 is a bottom plan view of the same;

Figure 6 is a rear end view of the same; and

Figure 7 is a vertical sectional view taken on the line

7—7 of Figure 2.

I claim:

The ornamental design for a spray valve, as shown.
